UNITED STATES PATENT OFFICE.

JAMES B. YEAKLE, OF BALTIMORE, MARYLAND.

WATCHMAN'S TIME-RECORDER AND SIGNAL.

SPECIFICATION forming part of Letters Patent No. 696,619, dated April 1, 1902.

Application filed December 10, 1900. Serial No. 39,259. (No model.)

To all whom it may concern:

Be it known that I, JAMES B. YEAKLE, a citizen of the United States, and a resident of Baltimore, in the State of Maryland, have 5 invented certain new and useful Improvements in Watchmen's Time-Recorders and Signals, of which the following is a specification.

My invention relates to that class of watchmen's time-recording systems in which the watchman as he makes his rounds sends the signal from various stations over an electric circuit by operating a push-button or other suitable circuit-closing device, the operation 15 of which is recorded upon a suitable time disk or sheet operated by clockwork at the superintendent's office or at other desired location. In this system should the watchman neglect to visit a certain part of the building and operate the apparatus at the station there such neglect may not be detected until the record at the office is examined some hours later.

The object of the invention is to provide a means whereby any such failure or neglect 25 may be immediately noticed or detected and the absence of the watchman promptly reported at the main supervisor's office—such, for instance, as the office of a district burglar-alarm telegraph company—and whereby measures 30 may then be taken to ascertain the cause of the watchman's failure to operate the apparatus at the station in the building where he is required to make his rounds.

My invention is especially useful in cases 35 where it is desirable to provide special attention at some particular point of the building, and the invention permits a strict surveillance of the watchman's movements, such that any neglect will be promptly observed and the 40 extra care required will be assured.

My invention consists, substantially, in the combination, with a watchman's time-recording system such as already described, of suitable means comprising an electric switch of 45 any desired character whereby the circuit-closing devices at the signal-stations to be visited by the watchman may be placed in connection with a transmitter adapted to transmit a signal over a circuit running to a 50 main supervisor's office, such as that of a district telegraph company. Such switch is preferably constructed to be under the control only of the superintendent of the building where the watchman makes his rounds or of

other person in authority and is so arranged 55 under a cover or seal that the watchman cannot observe the condition of the switch and may not, therefore, know whether the operation of the apparatus at his station is recorded upon the time-recorder or is sent to the main 60 or supervisor's office. By this apparatus the superintendent may change the circuits at the signal-station at any point on the watchman's rounds where it is desired that extra care should be exercised, and on a signal failing to come from said station at any time to the main or supervisor's office, as that of the district telegraph system, immediate steps may be taken to send a messenger to the place 65 and the cause of the failure be ascertained. 70

In the accompanying drawing I have illustrated my invention diagrammatically as carried out in connection with one form of watchman's electrical time-recorder and with a particular form of transmitter for sending the 75 signal to the district telegraph-office. The details of these devices may, however, be varied without departing from my invention, as may also the devices at the signal-station to be visited by the watchman and those at 80 the central office of the district telegraph system, since my invention consists in the broad combinations of apparatus as hereinafter described.

Referring to the drawing, 1 indicates a device typical of the devices used at each signal-station of the watchman's electrical time-recording system for sending a signal over a circuit 2 to a point where it is recorded on a suitable time disk or sheet. The device 1 is 90 here illustrated as consisting of an ordinary push-button adapted to close the circuit 2 when operated by the watchman in his rounds. As shown, the button has its circuit-closing parts inclosed within a suitable 95 box or casting, so as to be inaccessible to the watchman and make it impossible for him, should he be so disposed, to tamper with it.

Any desired number of stations may be provided, as will be understood in the art, said 100 stations being located at points to be visited by the watchman in his rounds. Any other circuit-closing device or devices to be operated by the watchman might be employed in place of the device 1, as well understood in 105 the art.

The time-recorder, which records the time when the watchman visits the stations, is here

typified by the disk 3, carrying the time-recording sheet and driven by a clockwork, a part of the train of which is shown, and an electromagnet 4, responsive to the signals 5 on the circuit 2 and adapted to actuate a stylus or marker to bring it in contact with the time-recording sheet 3.

6 is the usual battery or other generator of electricity for the circuit 2.

10 At each box or station to be visited by the watchman I provide a suitable switch (indicated at 7) adapted to change the connection of the apparatus operated by the watchman from the circuit including the time-recording 15 apparatus to a circuit or branch of circuit 8, which runs to and includes the electromagnet 9, of any suitable transmitter adapted to transmit a signal over a circuit 10, leading to the office of the district telegraph company 20 or other supervising authority.

The switch 7 is here shown as of the ordinary two-point form, but might be of any other desired form or character. It is placed in a suitable inclosure under lock and key, 25 so as to be free from interference by the watchman. The superintendent of the building, who has access to said switches, may at his pleasure change the same, so that the signal apparatus operated by the watchman will 30 act upon the magnet 9 instead of or in addition to the magnet 4. He may make this change at any station where he particularly desires that care should be exercised and may select any station at will for the purpose in 35 part of testing the care with which the watchman performs his duties, the watchman not knowing on which instrument his signal will be recorded. Said switch may be of any desired character, as before stated.

40 The transmitter operated or controlled by the magnet 9 may be the ordinary district-telegraph box or other device run by a clock-work or suitable power, which is released by the action of the magnet and which sends a 45 signal of any desired character over the circuit 10. As typical of such device I have illustrated a circuit make and break wheel 12 and a part of the train-wheelwork for operating the same, and a detent-lever 13, adapted 50 to free the train by disengaging a pin 14 on a wheel of the train, said detent-lever 13 being actuated by the armature of the electromagnet 9 in the obvious and well-known way.

55 The apparatus at the office of the district telegraph company consists of a signal-receiving device of the usual or any proper description. The one here shown comprises the usual main-line relay 15 and the local-circuit 60 apparatus, consisting of the bell-magnet 16 and the recorder-magnet 17.

It will be obvious that my invention permits of many changes in the details or elements making up the system. I do not limit myself 65 to any particular kind of switch 7 nor to organizing the same so that the time-recording magnet 4 will be switched out when the mag-

net 9 is switched in, the essence of my invention consisting in providing the magnet 9 with suitable means whereby the signal apparatus at the signal-stations visited by the watchman may at the will of the superintendent be placed in connection with said apparatus, so that the operation of the device at the signal-station will cause a signal to be sent to the main or supervisor's office, consisting of the district telegraph or other suitable main office independent of that comprising the time-recording device.

70 I claim as my invention—

75 1. The combination with a watchman's time-recording system having a series of signal-stations each provided with circuit-closing devices to be operated by the watchman on his rounds, and recording apparatus having an 80 operating or controlling magnet connected to the circuit of said devices, of a supervisory circuit containing signal-receiving apparatus, a signal-transmitter for said circuit, an electromagnet controlling the operation of the 85 same, a circuit connecting said electromagnet with the watchman's signal-stations, and suitable switches at said stations adapted to connect the circuit-closing devices at said stations with the circuit of said electromag- 90 net.

95 2. The combination in an electrical watchman's time-recorder system, of signal-stations connected with a suitable time-recorder over an electric circuit embracing the premises to 100 be guarded, an electric switch at each station controlling the connection of the apparatus to be operated by the watchman on his rounds and arranged to be inaccessible to the watchman, an independent signal-circuit, supervisory signal-receiving apparatus connected therewith, a transmitter on said circuit, a controlling-circuit leading from said signal-transmitter to the signal-stations, and a switch at each station inaccessible to the watchman 105 and operated to connect the apparatus operated by the watchman at said station with said controlling-circuit.

110 3. In a watchman's time-recorder and district or burglar alarm telegraph system, the 115 combination of a series of signal-stations, a recording mechanism, an electrical circuit connecting each of said stations with said recording mechanism, an independent signal-recording mechanism, a signal-transmitter 120 therefor, a controlling-circuit connecting the latter with each of the signal-stations, a circuit-closer at each station operated by the watchman, and a switch at each station inaccessible to the watchman and operated to 125 connect said circuit-closer with the controlling-circuit of said signal-transmitter.

Signed at Baltimore, in the State of Maryland, this 30th day of November, A. D. 1900.

JAMES B. YEAKLE.
